UNITED STATES PATENT OFFICE.

TANDY A. BRYSON, OF TROY, NEW YORK, ASSIGNOR TO TOLHURST MACHINE WORKS,
A CORPORATION OF NEW YORK.

SAFETY GUARD FOR CENTRIFUGAL EXTRACTORS.

Application filed February 18, 1921. Serial No. 446,017.

To all whom it may concern:

Be it known that I, TANDY A. BRYSON, a citizen of the United States, residing at Troy, in the county of Rensselaer and 5 State of New York, have made certain new and useful Improvements in Safety Guards for Centrifugal Extractors, of which the following is a specification.

The invention relates to safety guard devices for centrifugal extractors and more especially to novel devices of the kind wherein the guard automatically closes when the machine begins to rotate, is kept closed by the rotation of the machine, and is reusable for opening only after the machine has stopped rotating.

Objects and advantages of the invention will be set forth in part hereinafter and in part will be obvious herefrom, or may be learned by practice with the invention, the 20 same being realized and attained by means of the instrumentalities and combinations pointed out in the appended claims.

The invention consists in the novel parts, 25 constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a central, vertical section through 35 a centrifugal extractor embodying the invention, and showing the guard locked in closed position;

Fig. 2 is a fragmentary elevation, showing the guard latched in the open position;

Fig. 3 is a fragmentary top plan of the 40 hinge mounting on the casing for the guard, as indicated by line 3—3 of Fig. 1;

Fig. 4 is a horizontal section taken on line 4—4 of Fig. 1, showing the guard controlling mechanism in the open position by dotted lines, and by solid lines in the guard closing and locking position;

Fig. 5 is a fragmentary vertical section, 45 on an enlarged scale, of a locking device for the guard latch lever;

Fig. 6 is a fragmentary elevation, on an enlarged scale, of a different form of locking device for the guard latch operating bar;

Fig. 7 is a horizontal section on line 7—7 of Fig. 6;

Fig. 8 corresponds to Fig. 6 but shows the parts in unlocking position;

Fig. 9 is an enlarged detail in elevation, and in section on 9—9, of parts shown in Figs. 6 to 8; and

Fig. 10 is a detail of the upper left-hand parts of Figs. 6 and 8, showing the spring locking action.

The invention is shown applied to a solid curb or open top centrifugal extractor, and in certain aspects of the invention it is especially applicable to that type of machine, while in certain of its features it is applicable also to other kinds of centrifugal extractors.

In the exemplified and present preferred embodiment, the invention comprises as its main features a basket guard which is held or latched in open position against the action of gravity, and cooperating therewith 75 guard controlling mechanism which releases the guard so that the guard, merely by being released, will drop to the closed position. At the same time the guard controlling mechanism is automatically locked so as to prevent the guard being opened until the extractor has ceased rotating. The releasing and locking are effected by positive movement of the mechanism.

More particularly, in said present preferred embodiment, a latch lever is provided with a detent to hold up the open guard against gravity. A slideable bar is moved by the basket shaft to free the latch lever from its detent, thereby permitting the guard to drop to the closed position, and, the bar at the same time passes into locking position with the latch lever to lock the guard in closed position. In said embodiment, it will be understood, the guard closing and locking devices are also operated directly and positively from the basket and shaft and do not depend on any ancillary or secondary conditions or operations of the machine.

It will be understood that this preliminary general description is explanatory and not restrictive of the invention, and that other features of the invention will be first 5 set forth in connection with the following full detailed description.

Referring now in full detail to the embodiment of the invention illustrated by way of example in the accompanying drawings, a casing 1 is shown of the solid curb type, with the top opening of the casing and of the enclosed basket unobstructed, the drive being from beneath. The casing 1 is mounted on a frame 2, shown as of tripod 10 form. Enclosed within the casing 1 is a basket 3, provided with a central portion 4, supported upon and fixed to the upper end 5 of a shaft 6, which shaft is provided at its lower end with a belt pulley 7. The 15 shaft 6 is supported in a suitable bearing 8, the bearing being carried by the part 9 of the bottom of the casing 1. The parts so far as shown and described are more or less conventional in character, as various known 20 or suitable constructions may be employed.

By the present invention, a guard 15 closing the entire top opening of the casing is provided, and is shown as a flat cover, preferably of wire mesh or other open construction, 30 and of circular form to fit over and to close the opening 16 in the top of the casing and also thereby the opening 14 in the top of the basket. The guard closure 15 is shown with its edges bent around a stiffening and 35 supporting rod 17.

Means are provided for raising the closure 15 and holding it in raised or open position, as shown in Fig. 2, to give free access to the 40 openings in the top of the casing and of the basket. In accordance with one feature of the invention, as previously indicated, the closure 15 is held in such position that when released it will fall to the closing or safe position of Fig. 1 by the action of gravity.

As embodied, a hinge support or mounting for the closure 15 is fixed at or near the top outer peripheral edge of the casing 1, the hinge mounting comprising a leaf or plate 18 fastened to the closure 15 by suitable fastenings, such as bolts or rivets 19, which pass through the hinge, the guard and through a reenforcing plate 24 on the inside of the guard. The hinge leaf 18 is 50 pivotally mounted on a pin or rod 20, carried in lugs 21, which are formed on a curved plate 22, extending downwardly along the outer surface of the casing 1, and fastened thereto in suitable manner, as by screw bolts 23. From the hinge leaf 18 there 55 projects outwardly a lever 27, to which lever the guard-controlling mechanism is connected, and through which the closure is operated and controlled. An adjustable 60 stop 28 is provided for limiting the upward

movement of the guard 15, positioning it so 65 that it will be dropped by gravity into closed position when the basket begins to rotate. The positioning operation of this stop is shown in Fig. 2.

Referring now in detail to the present preferred and illustrated embodiment of the control mechanism for the safety guard or closure it is especially adapted to a bottom driven extractor, although the invention is applicable also to top driven or suspended machines as well. Said control mechanism comprises a latch lever 29, pivoted at 30 to the hinge lever 27, and extending downwardly outside the casing 1. Latch lever 29 at its bottom end is provided with a notch 32 adapted to cooperate with a detent 33, which is supported on the machine frame, and is adapted to hold the safety guard or closure in open position as 70 shown in Fig. 2.

Further, as embodied, the latch lever 29 is provided at its bottom end with a stop or contact surface 34, which is adapted to cooperate with the other parts of the safety mechanism to hold the guard in the closed or safe position as shown in Fig. 1. A spring 35 is preferably provided to yieldingly impel latch lever 29 inwardly to effect or to aid in its cooperation and coaction with the detent 33 and with the locking mechanism described hereinafter. Spring 35 is in tension and has one end hooked into latch lever 29 and the other end hooked into a bracket 36 fixed on the casing 1 of the extractor. The detent 33 is mounted upon a frame or support 39 carried upon and extending across between legs 37 and 38 of the machine frame, and being fastened thereto in suitable manner, as by screw bolts 40. The frame or support 39 is provided with a guide 42 for the latch lever 29, which holds it in alignment against possible transverse displacement, and limits its outward movement, the frame 39 limiting its inward movement.

The remaining portions of the guard control mechanism, as embodied, comprise means or mechanism, called into operation by the extractor beginning to rotate, which releases the latch lever 29 from the detent 33 and, after the guard 15 is in the closed or safety position, thereafter holds or locks the latch lever so that the guard may not again be opened until the extractor has stopped rotating and has come to rest.

In the embodied form of said means, a rod or bar 50 is supported at one end in the frame 2 and at the opposite end in the frame piece 39, bar 50 thereby having longitudinal movement to release the latch lever 29 from the detent 33 and then to hold or lock the latch lever 29 in closed or safe position. The end of lever 50 is shown beveled at 51

to form a nice operating fit to pass beneath and then lock the end 34 of the latch lever. The rod or bar 50 at its opposite end is provided with a hand piece 52 whereby the bar 5 is drawn backwardly, or to the left in Fig. 1, in the manual release or unlocking of the safety device, which is possible after the basket has come to rest.

Referring now to the embodied form of 10 mechanism for actuating the bar 50 in the manner indicated to close and to then lock the guard in safe position, the rod or bar 50 is not continuous, but is provided at its 15 central portion with an open frame 53, which is yoked about the shaft 6, the bar 50 extending along or substantially in alignment with a diameter of the shaft 6. The yoke frame 53, as shown, comprises two angled side pieces 48 and 49 fastened to the 20 ends of the two parts of bar 50 by bolts 47. The hub 54 of the pulley 7 extends upwardly within the yoke frame 53, and is provided with a horizontally disposed, outwardly projecting cam 55, which engages 25 with yoke 53 to slide bar 50, as later described.

For the purpose of locking bar 50 with its right hand end in holding or locking engagement with the bottom of latch lever 29, there are fixed on the bar 50 two lugs 56 30 and 57, with an open space therebetween. Mounted upon the adjacent leg 58 of the frame 2 are two lugs or brackets 59 and 60, in which are journaled a swingable locking bail 61. A lever arm 62 is fixed to one 35 end of the bail 61, whereby it may be rocked by hand out of locking position.

Means are provided by the invention for further or doubly guarding against any possible 40 manual release of the bar or rod 50 while the shaft 6 may be rotating very slowly just before coming to rest, that is, to prevent bar 50 being drawn to the right during the time elapsing between the cam 55 leaving the right hand end of yoke 53 and its re-engagement therewith. As embodied, 45 for this purpose, a retarding device is applied to bar 50, whereby the withdrawal of the bar to its guard-releasing or unlocking 50 position is rendered relatively slow, and this retarding action is regulated so that the latch lever 29 could not possibly be released from the bar 50 in the portion of a revolution of the shaft 6 in which the cam 55 would be 55 positioned so as to permit this. The embodied form of retarding device comprises a dash pot mechanism, including a cylinder 66 mounted on a bracket 67, and provided with a suitable piston 68 therewithin, having a piston rod 70 extending out from the open end of the cylinder, and connected to the bar 50 by a bracket 71. The opposite end of cylinder 66 is closed and is provided with an air vent 72. Thus the retraction 60 of bar 50 to the left in Fig. 1 is retarded

sufficiently so as to insure the guard from being unlocked until the shaft 6 has come to rest. It will usually be found unnecessary, however, to use the retarding device in most installations.

The manner of operation of the embodied mechanism as described, is substantially as follows:

It may be assumed that the mechanism is in the position of Fig. 2, with the guard 15 held open, and permitting free access to the extractor, the guard being inclined so that it will fall into closing or safe position by the action of gravity. It is held from falling, however, by the notch or latch 32 being in engagement with the detent 39, to which engaging position it is impelled by the spring 35. At this time the locking bail 61 is lying on top of lug 56, and rod 50 is in the retracted or left-hand position, as shown in Fig. 2, and as shown in dotted lines in Fig. 4.

When the machine is started into operation, the rotation of shaft 6 carries with it the cam 55, which engages with the inside of the right hand end of yoke 53, and thereby the rod or bar 50 is pushed to the right. This disengages the notch or latch 32 from detent 33, and the guard 15 falls immediately to the closed or safe position of Fig. 1. As the latch lever 29 moves upwardly due to the fall of guard 15, spring 35 draws the bottom end 34 of the latch lever over and upon the end 51 of bar 50, thereby locking the guard in closed position. The bail 61 also drops into the recess between the lugs 56 and 57, thereby holding the bar 50 in locked position.

If it be attempted to manually unlock the mechanism while the extractor is rotating, this will be prevented by the cam 55 on each revolution of the shaft 6 pushing the bar 50 to the right or rather preventing its being moved to the left. It will be understood that the latch lever will remain in the position of Fig. 1 until the guard 15 is raised by hand.

After shaft 6 has come to rest, by moving lever 62, locking-bail 61 is lifted out of its recess between lugs 56 and 57, and bar 50 is drawn to the left from the position of Fig. 1 to the position of Fig. 2, that is, from the full line position of Fig. 4 to the dotted line position thereof. After this is done, the guard 15 may be lifted, whereupon the latch lever 29 will move from the position of Fig. 1 to that of Fig. 2 and notch 32 will engage detent 33, and thereby will lock the guard 15 in raised or open position until the basket and its shaft are again started into rotation.

In accordance with one feature of the invention automatic locking means are provided for holding the latch lever 29 in locking position for the closed guard 15 rel-

atively to the locking bar 50, that is, means for preventing the latch lever being forcibly pried off the end of bar 50. Normally, this addition locking means will not be necessary, but may be provided when desired. In the present embodiment, said locking means is itself automatically locked by the movement to the right of the bar 50 to the position of Fig. 1, said means automatically unlocking when the bar 50 moves to the left to the position of Fig. 2.

In the embodied form of such means, a latch 110 lies substantially horizontally within a slot 111 which is formed in the right-hand end of the bar 50, the latch being pivoted on a pin 112, mounted in the bar 50. The latch 110 normally rests upon a pin 73 extending across the bottom part of the slot 111. The latch 110 is provided with a locking face 74, and when the latch is resting upon the pin 73, the upper surface 75 of this latch is flush with the beveled end 51 of the bar 50. On the under side of the latch 110 is a projection 76 which rides in a groove 77, formed in and extending downwardly from the under side of the opening in the frame piece 39 in which the bar 50 reciprocates.

The manner of operation of the locking device just described is substantially as follows:

When the bar is at the left-hand position, as shown in Fig. 1, latch 110 rests on pin 73, and the surface 75 of the latch is flush with the surface 51 of the bar. As bar 50 slides to the right to the position shown in Figs. 1 and 5, the latch 110 will slide beneath the bottom end of the latch lever 29. Just after the face 74 has passed the end of the latch lever 29, projection 76 rides upwardly on the right-hand end of the groove 77, thereby lifting latch 110 into the position shown in Fig. 5. In this position of the latch it would be impossible to pry the latch lever 29 off the end 51 of the bar 50. When bar 50 is slid back to the left from the position of Figs. 1 and 5 to the position of Fig. 2, projection 76 will ride downwardly in groove 77, and latch 110 will drop back on pin 73 and ride beneath the end of latch lever 29, permitting the latch lever to move downwardly to the position of Fig. 2 when the guard 15 is swung upwardly.

In Figs. 6 to 10 a different form of locking device for the bar 50 to hold it in the right hand position of Fig. 2 is provided, which may be substituted for the corresponding mechanism shown in Figs. 1, 2 and 4. These two mechanisms are alternative exemplary embodiments and are not restrictive of the invention. This form of locking means cooperates directly with devices on the basket shaft 6, said means locking directly and automatically as shaft 6

begins to rotate and pushes bar 50 to the right from the position of Fig. 2 to the position of Fig. 1, but can be disengaged or unlocked only after shaft 6 has come to rest.

In the embodied form of such means, a collar 80 is mounted on the shaft 6 or on the hub 54 of the pulley 7 to rotate therewith. The collar 80 is cut out into an annular recess 81 on its upper inner part, facing on the shaft 6 or pulley hub 54, and on its upper outer surface the collar is upwardly and inwardly beveled as shown at 82. The collar 80 is provided with a recess 83 in its outer vertical wall or periphery. Just beneath the collar 80 is an annular disc 84 loosely encircling the pulley hub 54, resting upon an annular ring 69 fixed on hub 54. This disc has a recess 85 in its outer part or periphery.

Means are provided for resiliently holding the disc 84 relatively to the collar 80 so as to maintain the recesses or slots 83 and 85 out of alinement with each other. As embodied, such means comprises a spring 86 having one end fastened to a pin 87, fixed in the collar 80, and having its other end fastened to a pin 88, fixed in the upper side of the disc 84. Two pins 89 and 90 project horizontally outwardly from the cylindrical vertical wall of the collar 80 adapted to engage with pin 88 and thereby to limit the movement in both directions of the disc 84 relatively to the collar 80. A finger piece 91 is fixed to the disc 84 whereby it may be conveniently rotated by hand relatively to the collar 80.

When spring 86 holds pin 88 on the disc against pin 89 on the collar, the recesses 83 and 85 are out of alinement, as shown in Figs. 6 and 7. When the disc 84 is pushed by finger piece 91 against the action of spring 86 until pin 88 in the disc strikes pin 90 on the collar, the recesses or slots 83 and 85 will be in alinement as shown in Fig. 8. The purpose of normally maintaining the slots 83 and 85 out of alinement is to prevent the unlocking of the locking means while shaft 6 is in motion, and the purpose of bringing these slots into alinement is to permit the manual unlocking of the locking device after shaft 6 comes to rest.

Referring now to the embodied form of locking means, a bracket 94 is mounted on the upper side of bar 50, and a locking device 95 is fixed to a pin 99 journaled in the bracket 94. The locking device 95 comprises a spring hook 96 having its hooked or detented end 97 beveled on its forward side to engage with and to ride up on the surface 82 of the collar 80 to effect the automatic locking action. A rigid projection 98 extends outwardly from the body of the locking device 95 to guard against any possi-

bility of the spring hook 96 being unwarrantedly pried upwardly or tampered with to unlock the device when the shaft 6 is rotating, although this would be a difficult 5 or impossible undertaking if this device were not used.

Projecting forwardly from the lower part 10 of the locking device 95 is a finger 100, adapted to pass beneath disc 84 and keep the device in locked position except when 15 the slots 83 and 85 are in register. A rigid tail 101 is fixed to the locking device 95 and projects backwardly from the pivot pin 99 and a coiled spring 102 is in compression beneath the tail 101, between it and the upper side of the bar 50. A handle 103 is fixed to the pin 99 whereby the locking device may be manually rocked to unlock 20 the bar 50 to permit its being moved to the left from the position of Fig. 1 to that of Fig. 2 after the shaft 6 has come to rest.

In Fig. 9 the side of the slot 85 is shown beveled or rounded at 104 and the top edges of the finger 100 are shown correspondingly beveled at 105, so that if by any chance finger 100 should be pressed upwardly into slot 85 it would immediately be pressed downwardly again into its proper position beneath disc 84. The forward end of finger 100 is also shown beveled at 106 to insure its passing smoothly under disc 84.

The manner of operation of the mechanism just described is substantially as follows:

35 As the shaft 6 begins to rotate, and the bar 50 is thereby moved by cam 55 on the basket shaft to the right from the position of Fig. 2 to that of Fig. 1, to release latch lever 29 from the detent 33, to cause guard 15 to drop to closing position, the locking device 40 95 will approach the collar 80. The spring hook 96 will ride upwardly on the beveled surface 82 of collar 80, as shown in Fig. 10, and as soon as the hook 96 has moved sufficiently to the right, it will snap down into the annular recess 81 in the collar 80 as 45 shown in Fig. 6. The bar 50 will move sufficiently to the right to give slight clearance between the hook 96 and the vertical 50 wall of the recess 81.

During the movement just described, the pin 100 has passed beneath the disc 84 and thus prevents the device 95 being rocked by the handle 103, and so maintains the bar 50 locked in the right-hand or safe position. The mechanism will be retained in this relation so long as shaft 6 continues to rotate. Shaft 6 is brought to rest with the slot 83 in line with the finger 100. By means of pin 91 the disc 84 will be rotated against the pull of spring 86 to move the disc from the position of Fig. 7 to that of Fig. 8, and thereby slots 83 and 85 are brought into alinement. Thereupon the handle 103 may be pressed downwardly against the action of

spring 102, and the bar 50 may be drawn to the left from the position of Fig. 1 to that of Fig. 2, and the guard 15 may thereupon be raised.

The invention in its broader aspects is 70 not limited to the specific mechanisms shown and described but departures may be made therefrom within the scope of the accompanying claims without departing from the principles of the invention and without sacrificing its chief advantages.

What I claim is:—

1. In combination in a centrifugal extractor a casing, a basket therewithin, a shaft extending downwardly from the basket, a guard for the open top of the casing hinged at a single place on the periphery of the casing and supported to fall into closed position when free, means for holding the guard open and released by the basket beginning to rotate to permit the guard to fall into closed position, means for preventing the reopening of the guard while the basket continues to rotate and manually operable means for releasing said preventing means after the basket has stopped rotating.

2. In combination in a centrifugal extractor a casing, a basket therewithin, a shaft extending downwardly from the basket, a guard for the open top of the casing hinged at a single place on the periphery of the casing, means for holding the guard open, means for releasing the holding means for allowing the guard to close upon the basket beginning to rotate, means for preventing the reopening of the guard while the basket continues to rotate and manually operable means for releasing said preventing means after the basket has stopped rotating.

3. In combination in a centrifugal extractor a casing, a rotatable basket therewithin, the basket and casing having an unobstructed top opening, a guard movable to completely cover or uncover said opening, and means operated by the basket starting into movement for permitting the guard to completely cover said opening, means for preventing the reopening of the guard while the basket continues to rotate and manually operable means for releasing said preventing means after the basket has stopped rotating.

4. In combination in a centrifugal extractor a casing, a rotatable basket therewithin, the basket and casing having an unobstructed top opening, a guard movable to completely cover or uncover said opening, and having a hinge mounted on the casing at the edge thereof, a latch lever connected to and extending downwardly from the hinge, a shaft extending downwardly from the basket, and means operated by the shaft for acting upon the latch lever to prevent the cover being raised while the shaft and

basket are rotating and manually operable means for releasing said preventing means after the shaft has come to rest.

5. In combination in a centrifugal extractor a basket, a shaft therefor, a guard therefor dropping by gravity to close the basket opening, a latch lever for holding the guard open and means operated by the basket shaft for releasing the latch lever to permit the guard to drop to closing position upon the basket beginning to rotate and for locking the latch lever and guard in basket closing position while the basket continues to rotate.

15. 6. In combination in a centrifugal extractor a basket, a guard dropping by gravity to close the basket opening, a latch lever connected to the guard and a cooperating detent for holding the guard in open position, a shaft for the basket, means operated directly by the basket shaft for releasing the latch lever from the detent as the shaft begins to rotate to permit the guard to drop to closing position, and for locking the guard and latch lever in closed position while the shaft continues to rotate.

7. In combination in a centrifugal extractor a casing and a basket therewithin, having an unobstructed opening, a hinge 30 on the casing, a guard supported on the hinge to drop by gravity to close said opening, a detent, a latch lever pivoted to the hinge, a spring impelling the latch lever into engagement with the detent, a shaft 35 extending downwardly from the basket, a sliding bar adapted to release the latch lever from the detent to permit the guard to drop and to engage the latch lever to lock the guard in closed position, a cam on the shaft 40 for sliding the bar to release the latch lever as the shaft begins to rotate and to prevent the retraction of the bar from its locking position while the shaft continues to rotate.

8. In combination in a centrifugal extractor a casing and a basket therewithin, having an unobstructed opening, a hinge on the casing, a guard supported on the hinge to drop by gravity to close said opening, a detent, a latch lever pivoted to the hinge, a spring 50 impelling the latch lever into engagement with the detent, a shaft extending downwardly from the basket, a sliding bar adapted to release the latch lever from the detent to permit the guard to drop and to engage the latch lever to lock the guard in closed position, a cam on the shaft for sliding the bar to release the latch lever as the shaft begins to rotate and to prevent the retraction of the bar from its locking position 55 while the shaft continues to rotate, and a locking device automatically locking the bar in locking position with respect to the latch lever but being manually releasable when the shaft comes to rest.

65. 9. In combination in a centrifugal ex-

tractor a basket guard, a latch lever holding the basket guard against gravity, a bar locking and unlocking the latch lever, and a member locking the latch lever and bar in locking position.

10. In combination in a centrifugal extractor, a basket and casing, a guard therefor, a latch lever connected to the guard and extending downwardly along the basket, a bar 75 slideable beneath the end of the latch lever to lock the guard in closed position and a member locking the latch lever in locking position on the bar.

11. In combination in a centrifugal extractor a basket, a shaft, a basket guard, locking mechanism for the guard including 80 a slideable bar, a detent collar on the shaft and a detent passing into locking engagement with said collar when the bar is slid to locking position.

12. In combination in a centrifugal extractor a basket, a shaft, a basket guard, locking mechanism for the guard including 90 a slideable bar, a detent collar on the shaft and a detent passing into locking engagement with said collar when the bar is slid to locking position, said detent being manually movable to free it from the detent collar.

13. In combination in a centrifugal extractor a basket, a shaft, a basket guard, locking mechanism for the guard including 95 a slideable bar, a detent collar on the shaft and a detent passing into locking engagement with said collar when the bar is slid to locking position, said detent being manually 100 rockable to free it from the detent collar.

14. In combination in a centrifugal extractor a basket, a shaft, a basket guard, locking mechanism for the guard including 105 a slideable bar, a detent collar on the shaft and a detent passing by spring action into locking engagement with said collar when the bar is slid to locking position.

15. In combination in a centrifugal extractor a basket, a shaft, a basket guard, locking mechanism for the guard including 110 a slideable bar, a detent collar on the shaft and a detent passing by spring action into locking engagement with said collar when the bar is slid to locking position, said detent being manually 115 movable to free it from the detent collar.

16. In combination in a centrifugal extractor a basket, a shaft, a basket guard, locking mechanism for the guard including 120 a slideable bar, a detent collar on the shaft and a detent passing by spring action into locking engagement with said collar when the bar is slid to locking position, said detent being manually 125 rockable to free it from the detent collar.

17. In combination in a centrifugal extractor, a basket, a shaft for the basket, a guard for the basket, means, including a locking bar, for locking the guard in closed 130

position, and means carried by the basket shaft, operating independently of the shaft speed for positively moving the locking bar to locking position as soon as the basket 5 starts rotating.

18. In combination in a centrifugal extractor, a basket, a shaft for the basket, a guard for the basket, means, including a locking bar, for locking the guard in closed 10 position, and eccentric means carried by the basket shaft, for positively moving the locking bar to locking position as soon as the basket starts rotating.

19. In combination in a centrifugal extractor, a casing, a rotatable basket, a guard 15 dropping by gravity to close the basket opening and means for holding the guard in open position and for releasing it therefrom, including a slideable member and a locking 20 latch therefor actuated by the rotation of the basket.

20. In combination in a centrifugal extractor, a casing, a rotatable basket, a guard 25 dropping by gravity to close the basket opening and means for holding the guard in open position and for releasing it therefrom, and positively holding it in closed position, said means being actuated by the rotation of the basket.

30 21. In combination in a centrifugal ex-

tractor, a basket, a basket shaft, a guard for the basket, a latch lever for the guard, a locking bar for the latch lever, and means carried by the basket shaft, operating independently of the shaft speed for moving the 35 locking bar into a position to lock the latch lever and guard in closed position, as soon as said shaft starts rotating.

22. In combination in a centrifugal extractor, a basket, a basket shaft, a guard 40 for the basket, a latch lever for the guard, a locking bar for the latch lever, and eccentric means carried by the basket shaft, for moving the locking bar into a position to lock the latch lever and guard in closed pos- 45 tion.

23. In combination in a centrifugal extractor, a basket, a basket shaft, a guard for the basket, a latch lever for the guard, a locking bar for the latch lever, and eccentric 50 means carried by the basket shaft for moving the locking bar into a position for locking the latch lever and guard in closed position, and for maintaining it in such locked position as long as the basket con- 55 tinues to rotate.

In testimony whereof, I have signed my name to this specification.

TANDY A. BRYSON.
